UNITED STATES PATENT OFFICE.

HARRY SWINGLEHURST, OF PHILADELPHIA, PENNSYLVANIA, ASSIGNEE, BY MESNE
ASSIGNMENTS, TO SCOTT & WILLIAMS, INCORPORATED, OF CAMDEN, NEW JERSEY,
A CORPORATION OF NEW JERSEY.

YARN-CHANGING DEVICE FOR KNITTING-MACHINES.

1,148,262.

Specification of Letters Patent.

Patented July 27, 1915.

Application filed July 29, 1910. Serial No. 574,540.

To all whom it may concern:

Be it known that I, HARRY SWINGLEHURST, a citizen of the United States, residing in Philadelphia, Pennsylvania, have invented 5 certain improvements in Yarn-Changing Devices for Knitting-Machines, of which the following is a specification.

The objects of my invention are to insure the positive removal of one yarn and the 10 equally positive insertion of the yarn which is to be substituted therefor, to provide for making the change quickly so that the number of needles to which the two yarns are both fed will be reduced to a minimum, to insure the clean severing of yarn which is removed, a firm retention of the severed end of the yarn and a positive engagement of the same with the needles when it is again introduced, and to prevent entanglement of 20 the yarns on their way to the guides.

These objects I attain in the manner hereinafter set forth, reference being had to the accompanying drawings, in which—

Figure 1 is a front view of the yarn changing device constructed in accordance with my invention; Fig. 2 is a side elevation of the same looking in the direction of the arrow *a* Fig. 1, and showing some of the parts of the machine in transverse section; Figs. 3 and 4 are views similar to Figs. 1 and 2 but omitting the thread separating plate; Fig. 5 is a plan or top view of the mechanism shown in Figs. 3 and 4; Fig. 6 is a view similar to Fig. 3, but showing the parts in a position different from that in which they are there illustrated; Fig. 7 is a view similar to Fig. 4 but showing the parts in the position which they have assumed in Fig. 6; Fig. 8 is a sectional plan view on the line *a*—*a*, Fig. 3, and Fig. 9 is a view illustrating a modification of part of the device.

In the drawings, 1 represents part of the dial cam plate of a knitting machine and 2 a ring fixedly mounted on the outer portion of the same. A ring 4 is mounted on the plate 1 so as to be capable of a limited amount of to-and-fro movement thereon, and a ring 3 is mounted upon the ring 2 so as to be susceptible of a like motion. The yarn changing, severing and retaining devices depend for their proper operation upon the movement of these two rings 3 and 4 to which the necessary motions can be imparted at the

desired times by mechanism under control 55 of a pattern chain in the usual manner, which mechanism forms no part of the present invention and need not therefore be described or illustrated.

Fixedly mounted on the ring 2 is a block 60 having its front portion recessed for the reception of vertically guided slides 7 and 9, said front portion of the block being provided at each side with a bracket 11 carrying a set screw 12, the purpose of which will 65 be hereinafter set forth. The slides 7 and 9 are retained in the grooves of the block 6 by means of cross bars 13 secured to the front of said block, and lifting force is constantly applied to each of the slides by 70 means of a coiled spring 14 contained in a vertical recess in the front portion of the block 6 and acting upon a bent pin 15, or other suitable bearing for the spring, projecting from the back of each of the slides 75 7 and 9. (See Figs. 3, 4 and 5.)

Depression of the slides 7 and 9 is effected by means of a wedge 16 secured to the front end of an arm 17 which projects from a hub 19 pivotally mounted upon a vertical post 80 20 projecting upwardly from the block 6. Projecting from the hub 19 in a reverse direction from the arm 17 is another arm 21, which is slotted for the reception of a pin 22 projecting upward from the ring 4, as 85 shown in Figs. 4 and 5.

When the parts are in the position shown in Figs. 3, 4, and 5, the wedge 16 depresses the slide 9 and permits the slide 7 to be raised by the action of its spring 14, and, 90 when the ring 4 is moved in the direction of the arrow *w* in Fig. 5, the wedge 16 will act to depress the slide 7 and will permit the slide 9 to be raised by the action of its spring, as shown in Fig. 6.

At the lower end of each of the slides 7 and 9 is a guide-eye *x* for one of the knitting yarns and when a slide is depressed the yarn from this guide-eye *x* will come within range of the hooks of the needles and will be 100 caught and knitted thereby, and when the slide is raised this guide-eye will direct the yarn above the hooks of the needles and said yarn will, therefore not be knitted, consequently the knitting can be effected by either 105 of the yarns, depending upon the adjustment of the slides, hence if one of the yarns is a heavy yarn and the other a light yarn,

either heavy or light fabric can be produced, as desired. When either of the slides is raised, however, so as to withdraw its yarn from range of the needle hooks, that yarn should be severed and the severed end retained until the slide is again lowered in order to bring its yarn into range of the needles. For this purpose I provide the front portion of the block 6, at one side of the same, with a fixed shear blade 23, and I pivotally mount at 24, upon the corresponding side of the block 6, a lever 25, which carries a shear blade 26, the blades coöperating to sever any yarn which may be directed between them; while their cutting edges are separated from one another. The lever 25 also carries a resilient plate 27 overlapping the blades 23 and 26 and bent at right angles, so as to lie alongside the inner face of the blade 23, as shown in Fig. 8, whereby a yarn extending from the guide-eye of an elevated slide and which has been severed by the closing of the shear blades 23 and 26 will be caught and held between the blade 23 and the plate 27, as shown in Fig. 8, until the corresponding slide is again lowered and the shear blades are opened for the reception of the yarn from the other slide which has meantime been raised. The lever 25 is slotted for the reception of a pin 29 projecting from the side of a bar 30 which is guided in a recess in one side of the block 6 and is prevented from escaping from said recess by means of a retainer plate 31, as shown in Figs. 4 and 5. The bar 30 is provided with a downwardly projecting pin 32 which enters a cam slot 33 in a plate 34 secured to the upper face of the ring 3, the cam slot being so formed that movement of the ring 3 in either direction will cause first an outward and then an inward movement of the bar 30 and consequently an outward, followed by an inward, swing of the lever 25, so as to permit of the separation of the shear blade 26 and clamp plate 27 from the shear blade 23 and thus release the yarn previously held thereby, and permit of the introduction of the other yarn which is severed, and its severed end retained, when the lever 25 swings inwardly again.

As but a slight movement of the rings 3 and 4 is necessary to effect the desired reversal in the position of the slides 7 and 9 and the operation of the shear blades, the yarns can be very quickly changed and the number of needles which receive both yarns can be reduced to a minimum, although if it is desired to provide for the feeding first of single yarn and then of double yarn to the needles, as in splicing, this can readily be effected by arresting the movement of the rings 3 and 4 when such movement is but

half completed, so as to retain both slides in the lowered position and the shear blades in the open position.

To prevent entanglement of the yarns on their way to the guide-eyes of the slides 7 and 9, I mount above the mechanism previously described, a separator plate 35 which occupies a position between the slides and 79 has, projecting from each side of it, an arm 36, each of these arms being provided with a guide-eye for its respective yarn, the latter passing from this guide-eye through the guide-eye of the slide which controls that yarn. The separator plate is mounted upon the block 6 by means of a bent arm 37 secured to one side of said plate, as shown in Fig. 1.

The usual latch opener and guard plate is represented at 39, the same being mounted so as to be vertically adjustable upon a bracket 40 projecting upwardly from the ring 2 at a point inside of the ring 3.

When it is desired to impart positive motion to the slides 7 and 9 in both directions, the springs 14 may be dispensed with and a plate 16^a having a wedge-shape slot therein may take the place of the wedge 16, said wedge-shaped slot receiving pins 41 which project from the slides 7 and 9, as shown in Fig. 9.

I claim:

1. In yarn changing mechanism for knitting machines, the combination of a pair of slides each movable from and toward the needles and having a yarn guide, a wedge movable across said slides, and means for operating said wedge whereby it may be caused to project either slide and permit retraction of the other slide simultaneously with such projection, said operating means comprising a lever carrying said wedge and a ring movable on that part of the machine which carries the yarn changing mechanism, and having means for directly engaging said lever.

2. In yarn changing mechanism for knitting machines, the combination of yarn guides disposed side by side, means for moving the same to operative or inoperative relation with the needles, and a separator plate occupying a position between the yarns as they pass to the yarn guides, said separator plate having on each side of the same a guide-eye for the yarn passing alongside of the plate.

In testimony whereof, I have signed my name to this specification, in the presence of two subscribing witnesses.

HARRY SWINGLEHURST.
